[57] ABSTRACT

Compounds of the formula

wherein X is various amino or imino acids and esters are disclosed. These compounds are useful due to their angiotensin converting enzyme inhibition activity and depending upon the definition of X may also be useful as analgesics due to their enkephalinase inhibition activity.

6 Claims, No Drawings

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.

UREIDO AMINO AND IMINO ACIDS,
COMPOSITIONS AND METHODS FOR USE

FIELD OF THE INVENTION

The present invention relates to ureido amino and imino acid compounds and more particularly concerns such compounds, compositions including such compounds and methods for their use.

BACKGROUND OF THE INVENTION

Almqvist et al., "Synthesis and Biological Activity of a Ketomethylene Analogue of a Tripeptide Inhibitor of Angiotensin Converting Enzyme", *J. Med. Chem.*, 1980, 23, 1392-1398, discloses the ketomethylene compound the formula

This and related compounds are also disclosed by Almqvist et al. in U.S. Pat. No. 4,329,473.

Natarajan et al. in U.S. Pat. No. 4,621,092 disclose compounds of the formula

These compounds are useful as hypotensive agents due to their angiotensin converting enzyme inhibition activity and depending upon the definition of X may also be useful as analgesics due to their enkephalinase inhibition activity.

Godfrey, Jr. et al. in U.S. Pat. No. 4,604,402 disclose compounds of the formula

These compounds are useful as hypotensive agents due to their angiotensin converting enzyme inhibition activity and depending upon the definition of X may also be useful as analgesics due to their enkephalinase inhibition activity.

SUMMARY OF THE INVENTION

In accordance with the present invention novel ureido imino and amino acid compounds useful, for example, as hypotensive agents are disclosed. The vari-

ous ureido-keto and hydroxy-substituted ureido compounds have the general formula

wherein

10 R1 is hydrogen, lower alkyl, halo substituted lower alkyl,

20 -(CH2)m-cycloalkyl, -(CH2)2-NH2, -(CH2)3-NH2,
-(CH2)4-NH2,

25 -(CH2)q-SH, (CH2)q-OH, -(CH2)q-S-lower alkyl,

30 n is one or two,
R2 is

35 R3 and R4 are independently selected from hydrogen, lower alkyl,

40 -(CH2)r-cycloalkyl, -(CH2)r-NH2, -(CH2)r-Cl,

-continued

R₂₄ is hydrogen,R₂₅ is hydrogen, lower alkyl,R₂₆ is lower alkyl, $-(CH_2)_q-$ cycloalkyl, $-(CH_2)_q-$ m is zero or an integer from 1 to 4,
r is an integer from 1 to 7,
q is an integer from 1 to 4,

X is an amino or imino acid or ester of the formula

-continued

R₇ is hydrogen, lower alkyl, halogen, hydroxy,

a 1- or 2-naphthyl of the formula

a substituted 1- or 2-naphthyl of the formula

20 a 1- or 2-naphthoxy of the formula

25

30 a substituted 1- or 2-naphthoxy of the formula

50 a 1- or 2-naphthylthio of the formula

55 or a substituted 1- or 2-naphthylthio of the formula

60

R₈ is lower alkyl, halogen,

—O—lower alkyl, a 1- or 2-naphthoxy of the formula

a substituted 1- or 2-naphthoxy of the formula

a 1- or 2-naphthylthio of the formula

or a substituted 1- or 2-naphthylthio of the formula

R_9 is lower alkyl, keto,

-continued

R_{10} is halogen or $\text{Y}-\text{R}_{16}$.

R_{11} , R'_{11} , R_{12} or R'_{12} are independently selected from hydrogen and lower alkyl or R'_{11} , R_{12} and R'_{12} are hydrogen and R_{11} is

20

R_{13} is lower alkyl of 1 to 4 carbons, lower alkoxy of 1 to 4 carbons, lower alkylthio of 1 to 4 carbons, chloro, bromo, fluoro, trifluoromethyl, hydroxy, phenyl, phenoxy, phenylthio, or phenylmethyl.

25

R_5 is lower alkyl of 1 to 4 carbons, lower alkoxy of 1 to 4 carbons, lower alkylthio of 1 to 4 carbons, chloro, bromo, fluoro, trifluoromethyl or hydroxy.

30

R_6 is hydrogen, lower alkyl, benzyl, benzhydryl, alkali metal salt ion, alkaline earth metal salt ion,

$-\text{CH}(\text{R}_{17})-\text{O}-\text{C}(=\text{O})-\text{R}_{18}$,

35

or $-(\text{CH}_2)_2\text{Si}(\text{CH}_3)_3$.

p is one, two or three provided that p is more than one only if R_{13} or R_5 is methyl, methoxy, chloro, bromo or fluoro.

R_{14} is hydrogen, lower alkyl,

45

50

R_{15} is hydrogen or lower alkyl of 1 to 4 carbons.

Y is oxygen or sulfur.

R_{16} is lower alkyl of 1 to 4 carbons,

55

60

or the R_{16} groups join to complete an unsubstituted 5- or 6-membered ring or said ring in which one or more of the carbons has a lower alkyl of 1 to 4 carbons of a di(lower alkyl of 1 to 4 carbons) substituent.

R_{17} is hydrogen, lower alkyl, cycloalkyl, or phenyl.

65

R_{18} is hydrogen, lower alkyl, lower alkoxy, or phenyl.

v is zero, one, or two

R_{19} is lower alkyl or

R₂₀ is hydrogen, lower alkyl,

R_{21} is hydrogen, lower alkyl,

$-(CH_2)_r-NH_2$, $-(CH_2)_r-SH$, $-(CH_2)_r-S-$ lower alkyl,

R_{22} is lower alkyl, benzyl, or phenethyl.

R₂₃ is hydrogen, lower alkyl, benzyl, or phenethyl. 60

DETAILED DESCRIPTION OF THE INVENTION

This invention is directed to the various novel ureido-keto and hydroxy-substituted ureido imino and amino acid compounds of formula I above, and compositions and methods of using compositions containing the novel compounds. 65

The term lower alkyl used in defining various symbols refers to straight or branched chain radicals having up to seven carbons. The preferred lower alkyl groups are up to four carbons with methyl and ethyl most preferred. Similarly the terms lower alkoxy and lower alkythio refer to such lower alkyl groups attached to an oxygen or sulfur.

The term cycloalkyl refers to saturated rings of 3 to 7 carbon atoms with cyclopentyl and cyclohexyl being most preferred.

The term halogen refers to chloro, bromo and fluoro.

The term halo substituted lower alkyl refers to such lower alkyl groups described above in which one or more hydrogens have been replaced by chloro, bromo or fluoro groups such as trifluoromethyl, which is preferred, pentafluoroethyl, 2,2,2-trichloroethyl, chloromethyl, bromomethyl, etc.

The symbols

30 represent that the alkylene bridge is attached to an available carbon atom.

R_2 is

45 is reacted with a chlorocarbonate of the formula

in the presence of a base, such as triethylamine or diisopropylethylamine followed by diazomethane to provide a compound of the formula

Compound IV is reacted with amine of the formula

tecting group is removed by hydrogenation, treatment with acid, or other known methods following completion of the reaction sequence.

The ester products of formula I wherein R₆ is lower alkyl, benzyl or benzhydryl can be chemically treated such as with sodium hydroxide in aqueous dioxane or with trimethylsilyl bromide to yield the products of formula I wherein R₆ is hydrogen. The benzyl and benzhydryl esters can also be hydrogenated, for example by treating with hydrogen in the presence of a palladium on carbon catalyst.

The ester products of formula I wherein R₆ is

may be obtained by employing the acid chloride of formula VIII in the above reactions with such ester group already in place. Such ester reactants can be prepared by treating the corresponding amino or imino acid of the formula

HX

XV

wherein R₆ is hydrogen with an acid chloride such as

so as to protect the N-atom. The protected amino or imino acid is then reacted in the presence of a base with a compound of the formula

wherein L is a leaving group such as chlorine, bromine, tolylsulfonyl, etc., followed by removal of the N-protecting group such as by treatment with acid or hydrogenation.

The ester products of formula I wherein R₆ is

can also be obtained by treating the product of formula I wherein R₆ is hydrogen with a molar excess of the compound of formula XVI.

When the compounds of formula I contain a reactive sulfur atom within the amino acid portion of the molecule, i.e. X is

for example, then the above described procedures are somewhat altered to avoid the use of hydrogenation to remove the N-protecting groups. For example, the N-protecting group used should be those which are compatible with acid removal such as benzyloxycarbonyl, t-butyl and the like.

The compounds of formula I wherein R₆ is hydrogen form salts with a variety of inorganic or organic bases. The nontoxic, pharmaceutically acceptable salts are preferred, although other salts are also useful in isolating or purifying the product. Such pharmaceutically acceptable salts include metal salts such as sodium, potassium or lithium, alkaline earth metal salts such as calcium or magnesium, and salts derived from amino acids such as arginine, lysine, etc. The salts are obtained by reacting the acid form of the compound with an equivalent of the base supplying the desired ion in a medium in which the salt precipitates or in aqueous medium and then lyophilizing.

Similarly, the compounds of formula I, especially wherein R₆ is an ester group, form salts with a variety of inorganic and organic acids. Again, the non-toxic pharmaceutically acceptable salts are preferred, although other salts are also useful in isolating or purifying the product. Such pharmaceutically acceptable salts include those formed with hydrochloric acid, methanesulfonic acid, sulfuric acid, maleic acid, etc. The salts are obtained by reacting the product with an equivalent amount of the acid in a medium in which the salt precipitates.

As shown above, the amino or imino acid portion of the molecule of the products of formula I is in the L-configuration. Several asymmetric centers are also present in the balance of the molecule as represented by the * in formula I. Thus the compounds of formula I can exist in diastereoisomeric forms or in mixtures thereof. The above described processes can utilize racemates, enantiomers or diastereomers as starting materials. When diastereomeric products are prepared, they can be separated by conventional chromatographic or fractional crystallization methods.

The products of formula I wherein the imino acid ring is monosubstituted give rise to cis-trans isomerism. The configuration of the final product will depend upon the configuration of the R₇, R₈ and R₉ substituent in the starting material of formula XV.

The compounds of formula I, and the pharmaceutically acceptable salts thereof, are hypotensive agents. They inhibit the conversion of the decapeptide angiotensin I to angiotensin II and, therefore, are useful in reducing or relieving angiotensin related hypertension. The action of the enzyme renin on angiotensinogen, a pseudoglobulin in blood, produces angiotensin I. Angiotensin I is converted by angiotensin converting enzyme (ACE to angiotensin II. The latter is an active pressor substance which has been implicated as the

causative agent in several forms of hypertension in various mammalian species, e.g. humans. The compounds of this invention intervene in the angiotensinogen $\rightarrow$ (renin) $\rightarrow$ angiotensin I $\rightarrow$ angiotensin II sequence by inhibiting angiotensin converting enzyme and reducing or eliminating the formation of the pressor substance angiotensin II. Thus by the administration of a composition containing one (or a combination) of the compounds of this invention, angiotensin dependent hypertension in a species of mammal (e.g. humans) suffering therefrom is alleviated. A single dose, or preferably two to four divided daily doses, provided on a basis of about 0.1 to 100 mg, preferably about 1 to 50 mg, per kilogram of body weight per day is appropriate to reduce blood pressure. The substance is preferably administered orally, but parenteral routes such as the subcutaneous, intramuscular, intravenous or intraperitoneal routes can also be employed.

The compounds of this invention can also be formulated in combination with a diuretic for the treatment of hypertension. A combination product comprising a compound of this invention and a diuretic can be administered in an effective amount which comprises a total daily dosage of about 30 to 600 mg, preferably about 30 to 330 mg of a compound of this invention, and about 15 to 300 mg, preferably about 15 to 200 mg of the diuretic, to a mammalian species in need thereof. Exemplary of the diuretics contemplated for use in combination with a compound of this invention are the thiazide diuretics, e.g. chlorothiazide, hydrochlorothiazide, flumethiazide, hydroflumethiazide, bendroflumethiazide, methylchlorothiazide, trichloromethiazide, polythiazide or benzthiazide as well as ethacrynic acid, ticrynafen, chlorthalidone, furosemide, musolimine, bumetanide, triamterene, amiloride and spironolactone and salts of such compounds.

The compounds of formula I can be formulated for use in the reduction of blood pressure in compositions such as tablets, capsules or elixirs for oral administration, or in sterile solutions or suspensions for parenteral administration. About 10 to 500 mg of a compound of formula I is compounded with physiologically acceptable vehicle, carrier, excipient, binder, preservative, stabilizer, flavor, etc., in a unit dosage form as called for by accepted pharmaceutical practice. The amount of active substance in these compositions or preparations is such that a suitable dosage in the range indicated is obtained.

The compounds of formula I wherein X is

also possess enkephalinase inhibition activity and are useful as analgesic agents. Thus, by the administration of a composition containing one or a combination of such compounds of formula I or a pharmaceutically acceptable salt thereof, pain is alleviated in the mammalian host. A single dose, or preferably two to four divided daily doses, provided on a basis of about 0.1 to about 100 mg per kilogram of body weight per day, preferably about 1 to about 50 mg per kilogram per day, produces the desired analgesic activity. The composition is preferably administered orally but parenteral routes such as subcutaneous can also be employed.

Preferred compounds of this invention with respect to the amino or imino acid part of the structure are those wherein

R_7 is hydrogen, hydroxy, chloro, fluoro, lower alkyl of 1 to 4 carbons, cyclohexyl, amino, —O-lower alkyl wherein lower alkyl is of 1 to 4 carbons, —S-lower alkyl wherein lower alkyl is of 2 to 4 carbons,

m is zero, one or two.

R_{13} is methyl, methoxy, chloro, fluoro, bromo, methythio, or hydroxy.

t is 2 or 3.

R_{21} is hydrogen, straight or branched chain lower alkyl of 1 to 4 carbons,

R₃ isR₄ is methyl, n-butyl, or -(CH₂)₄-NH₂.
R₂₄ is hydrogen,

The present invention will now be described by the following examples, however the invention is not meant to be limited to the details therein.

EXAMPLE 1

1-[[[(S)-3-[[N²-(Cyclobutylcarbonyl)-L-lysyl]-amino]-2-oxo-4-phenylbutyl]methyl-amino]carbonyl]-L-proline, 1.5 hydrochloride

A.

N²-(Cyclobutylcarbonyl)-N⁶-[(phenylmethoxy)-carbonyl]-L-lysine

N⁶-[(Phenylmethoxy)carbonyl]-L-lysine (4.73 g, 16.9 mmole) was suspended in 50 ml of acetonitrile and thereafter bis(trimethylsilyl)trifluoroacetamide (18.5 ml, 17.92 g, 69.6 mmol) was added. After stirring the mixture for 45 minutes under argon, it became homogeneous. After cooling to 5° C., a solution of cyclobutane carboxylic acid chloride (2.02 g, 17 mmol) in 10 ml of tetrahydrofuran was added dropwise over 15 minutes. The reaction mixture was stirred for 2 hours and then partitioned between ethyl acetate and water. The ethyl acetate layer was concentrated to an oil, dissolved in a saturated bicarbonate solution and washed with ethyl acetate. The aqueous layer was acidified to pH 7 with concentrated hydrochloric acid and extracted with ethyl acetate. This ethyl acetate extract was dried over sodium sulfate and concentrated in vacuo to give the title A compound (5.46 g, 15.5 mmol).

B.

(S)-[3-Chloro-2-oxo-1-(phenylmethyl)propyl]-carbamic acid, 1,1-dimethylethyl ester

To a stirred solution of benzyloxy carbonyl-L-phenylalanine (26.5 g, 100 mmol) in tetrahydrofuran (150 ml) at -20° was added isobutylchloroformate (13 ml, 100 mmol). N-methylmorpholine (11 ml, 100 mmol) was then added in drops. The solution was stirred between -15° and -20° for fifteen minutes and was filtered. Tetrahydrofuran (25 ml) was used for the washings. This was added to a cold (ice bath) ethereal solution of diazomethane in drops. After the addition was over, the ice bath was removed and the reaction mixture was stirred at ambient temperature for 2 hours. Nitrogen was blown over the solution and the volume was reduced to 400 ml. The reaction mixture was then stirred in an ice bath and hydrochloric acid in acetic acid (2N, 55 ml) was added in drops. After the addition was over,

the ice bath was removed and the reaction mixture stirred for fifteen minutes at room temperature. The reaction mixture was evaporated in vacuo and the residue on attempted dissolution in ether afforded 6.2 g of the title B compound. The mother liquor on concentration and after crystallization from ether/hexane afforded another 17.65 g of the title B compound.

C.

10 (S)-[3-[Methyl(phenylmethyl)amino]-2-oxo-1-(phenylmethyl)propyl]carbamic acid, 1,1-dimethylethyl ester, p-toluenesulfonate salt

A solution of the compound of part B (6.45 g, 21.65 mmole), benzylmethylamine (2.78 ml, 21.55 mmole), 15 NaHCO₃ (2.18 g, 26 mmole) and sodium iodide (1.62 g, 10.83 mmole) in dimethylformamide (75 ml) was stirred under argon at room temperature for 4 hours. The resulting mixture was concentrated in vacuo, diluted with ether, washed three times with water and extracted five times with 1N hydrochloric acid. The combined extracts were made basic using NaHCO₃ (solid) and extracted three times with ethyl acetate. The combined ethyl acetate extracts were dried over magnesium sulfate, concentrated and the residue was dissolved in ether. To this solution was added a warm solution of p-tolene-sulfonic acid (2.93 g, 15.4 mmole) in ethyl acetate. The resulting orange solution was seeded with product crystals from an earlier run and cooled until crystallization was complete. The resulting crystalline solid was collected and washed with ether to give the title C compound (7.43 g, 13.40 mmole).

D.

35 (S)-[3-(Methylamino)-2-oxo-1-(phenylmethyl)-propyl]-carbamic acid, 1,1-dimethylethyl ester, p-toluenesulfonate(1:1)salt

A solution of the compound of part C (7.33 g, 13.2 mmole) and palladium dihydroxide in methanol was stirred under a positive pressure of hydrogen for 3 hours. The resulting solution was filtered and concentrated. The product was crystallized from ether to give the title D compound (5.82 g, 12.53 mmole).

E.

40 (S)-1-[[3-[(1,1-Dimethylethoxy)carbonyl]-amino]-2-oxo-4-phenylbutyl]methylamino]-carbonyl]-L-proline, phenylmethyl ester

To a stirring solution of L-proline benzyl ester hydrochloride (6.05 g, 25 mmole) in methylene chloride (100 ml) at -30° C. were added N-methyl morpholine (6.9 ml, 62.5 mmole) and phosgene (40 ml, 48 mmole, 12 percent in benzene). The resulting solution was stirred at -30° for one hour and at room temperature for an additional hour. The mixture was concentrated at reduced pressure and to the residue was added methylene chloride (60 ml), a solution of the compound of part D (7.75 g, 16.68 mmole) in methylene chloride (100 ml) and N-methyl morpholine (5.5 ml, 50 mmole). The resulting mixture was stirred at room temperature overnight and concentrated. The residue was dissolved in ethyl acetate, washed with water, 1N hydrochloric acid, and 10 percent NaHCO₃, dried over magnesium sulfate and concentrated to an orange oil. The crude product was chromatographed on silica gel. Fractions containing the desired product were combined and concentrated to give the title E compound as a beige foam (7.17 g, 13.7 mmole).

21

F

(S)-1-[[[(3-Amino-2-oxo-4-phenylbutyl)methylamino]carbonyl]-L-proline, phenylmethyl ester, monohydrochloride

A solution of the compound of part E (7.12 g, 13.6 mmole) was stirred in a saturated solution of hydrochloric acid/ethyl acetate for one hour. The resulting precipitate was collected and washed with ethyl acetate to give the title F compound.

G.

1-[[[(S)-3-N²-(Cyclobutylcarbonyl)-N⁶-[(phenylmethoxy)carbonyl]-L-lysyl]amino]-2-oxo-4-phenylbutyl]-methylamino]carbonyl]-L-proline phenylmethyl ester, 1.5 hydrochloride

To a solution of the compound of part A (0.54 g, 1.5 mmol) in 20 ml of dimethylformamide -50° C. and under nitrogen was added triethylamine (0.21 ml, 1.5 mmol) and isobutylchloroformate (0.19 ml, 1.5 mmol). After 20 minutes of stirring at -50° C. a solution of the compound of part F (0.69 g, 1.5 mmol) in 10 ml of dimethylformamide was added, followed quickly by the addition of diisopropylethyl amine (0.26 ml, 1.5 mmol). The internal temperature rose to -35° C. After stirring overnight (from -35° C. to room temperature) the reaction mixture was poured into 100 ml of water and extracted three times with ethyl acetate. The combined ethyl acetate extracts were washed twice with saturated sodium hydrogen carbonate, twice with 10 percent potassium hydrogen sulfate, twice with water and dried over magnesium sulfate. The so-treated extracts were thereafter concentrated under reduced pressure to give a yellow oil. Purification by flash chromatography and recrystallization from ethyl acetate/hexane afforded the title G compound as white crystals (0.49 g).

H.

1-[[[(S)-3-[[N²-(Cyclobutylcarbonyl)-L-lysyl]amino]-2-oxo-4-phenylbutyl]methylamino]carbonyl]-L-proline, 1.5 hydrochloride

A solution of the compound of part G (0.25 g, 0.32 mmol) in 50 ml of ethanol containing 1N hydrochloric acid (0.64 ml, 0.64 mmol) and 10 percent palladium on

22

carbon was hydrogenated overnight. The reaction mixture was filtered and the filtrate was concentrated. The solid residue was triturated with ether and the product was lyophilized in double distilled water two times affording the title compound as a fluffy white solid (0.14 g).

EXAMPLE 2

10 1-[[[(S)-3-[[N²-(Cyclobutylcarbonyl)-L-lysyl]amino]-2-hydroxy-4-phenylbutyl]methylamino]carbonyl]-L-proline, 1.5 hydrochloride

A.

15 1-[[[(S)-3-[[N²-(Cyclobutylcarbonyl)-N⁶-[(phenylmethoxy)carbonyl]-L-lysyl]amino]-2-hydroxy-4-phenylbutyl]methylamino]carbonyl]-L-proline phenylmethyl ester, 1.5 hydrochloride

A sample of the compound from part G of Example 1 was dissolved in ethanol (15 ml). While stirring in an ice bath, sodium borohydride (150 mg, 3.95 mmol) was added. The solution was stirred at room temperature for 90 minutes. It was then evaporated, taken into ethyl acetate and washed with 10 percent aqueous potassium hydrogen sulfate solution. The ethyl acetate solution (after evaporation) was chromatographed over silica gel to obtain 1.1 grams of the title A compound.

20 30 B 1-[[[(S)-3-[[N²-(Cyclobutylcarbonyl)-L-lysyl]amino]-2-hydroxy-4-phenylbutyl]-methylamino]carbonyl]-L-proline, 1.5 hydrochloride

The compound from part A of this Example was thereafter treated using the procedures of part H in Example 1 to obtain the title compound.

EXAMPLES 3-30

Using the methods and procedures described above and in Examples 1 and 2, the following additional compounds of the present invention can be made.

45

What is claimed is:

1. A compound of the formula

5

10

or a pharmaceutically acceptable salt thereof wherein
 R_1 is hydrogen, lower alkyl,

15

$-(\text{CH}_2)_m$ -cycloalkyl, $-(\text{CH}_2)_2-\text{NH}_2$, $-(\text{CH}_2)_3-\text{NH}_2$, $-(\text{CH}_2)_4-\text{NH}_2$;

20

n is one or two;

R_2 is

30

R_3 and R_4 are independently selected from hydrogen, lower alkyl,

35

40

$-(\text{CH}_2)_r$ -cycloalkyl, $-(\text{CH}_2)_r-\text{NH}_2$, CF_3 ,

45

50

R_{24} is hydrogen,

55

R_{25} is hydrogen, lower alkyl,

65

$-(\text{CH}_2)_m$ -cycloalkyl, or

R_{26} is lower alkyl, $-(\text{CH}_2)_q$ -cycloalkyl,

m is zero or an integer from 1 to 4,

r is an integer from 1 to 7,

q is an integer from 1 to 4,

R_7 is hydrogen or lower alkyl;

R_5 is lower alkyl of 1 to 4 carbons, lower alkoxy of 1 to 4 carbons, lower alkylthio of 1 to 4 carbons, chloro, bromo, fluoro, trifluoromethyl or hydroxy,

R_6 is hydrogen, lower alkyl, benzyl, benzhydryl, alkali metal salt ion, alkaline earth metal salt ion

or $-(\text{CH}_2)_2\text{Si}(\text{CH}_3)_3$; and

p is one, two or three provided that p is more than one only if R_5 is methyl, methoxy, chloro, bromo or fluoro.

2. A compound of claim 1 wherein

n is one;

R_1 is $-\text{CH}_3$ or $-(\text{CH}_2)_4-\text{NH}_2$;

R_2 is

R_3 is

R_4 is methyl, n-butyl, or $-(\text{CH}_2)_4-\text{NH}_2$, and

R_{24} is hydrogen,

3. The compound of claim 1 wherein

R_1 is methyl;

R_2 is

R_3 is

R₄ is $-\text{CH}_2)_4-\text{NH}_2$

R₆ is hydrogen; and

R₂₄ is

4. The compound of claim 1 having the name 1-
[[[(S)-3-[[N²-(cyclobutylcarbonyl)-L-lysyl]-amino-2-
oxo-4-phenylbutylmethylamino]carbonyl]-L-proline,
1.5 hydrochloride.

5. The compound of claim 1 wherein

R₁ is methyl;

R₂ is

5
R₃ is

10

15 R₄ is $-(\text{CH}_2)_4-\text{NH}_2$;
R₆ is hydrogen;
R₂₄ is

20

6. The compound of claim 1 having the name 1-[[[(S)-
3-[[N²-(Cyclobutylcarbonyl)-L-lysyl]-amino-2-
hydroxy-4-phenylbutyl]methylamino]carbonyl]-L-pro-
line, 1.5 hydrochloride.
